UNITED STATES PATENT OFFICE.

LEVI BOWERS, OF MARTINSBURG, PENNSYLVANIA.

STRAW-STACKER.

SPECIFICATION forming part of Letters Patent No. 292,279, dated January 22, 1884.

Application filed November 17, 1883. (No model.)

To all whom it may concern:

Be it known that I, LEVI BOWERS, a citizen of the United States, residing at Martinsburg, in the county of Blair and State of Pennsylvania, have invented certain new and useful Improvements in Straw-Stackers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of the invention, and is a side elevation. Fig. 2 is a rear elevation of the separator, the straw-carrier being shown in longitudinal section; and Fig. 3 is a detail view of the hinge of one of the carrier-rails.

This invention has relation to straw-stackers; and it consists in the construction and novel arrangement of devices, as will be herein-after fully described, and particularly pointed out in the claim appended.

Referring by letter to the accompanying drawings, *a* designates the thrashing-machine, to which the improved side stacker is removably attached. The sill *b* of the stacker is connected to the sill *e* of the thrasher by a hook, *c*, on its under face, said hook *c* engaging a stud or screw, *d*, on the under face of the sill *e*. A brace-rod, *f*, connects the sill *b* with the top cross-bar, *g*, of the thrasher, and a brace-rod, *h*, connects it with the sill *e'* of the thrasher, and a stop, *i'*, is removably secured to the outside of the sill *e* of the thrasher, to prevent, in connection with the brace-rods, lateral movement of the stacker. At the rear end of the thrasher, and just above the sills *e* *e'*, a shaft, *i*, provided with a miter-gear wheel, *i'*, near each end, is journaled in boxes *i* *i'*, and has a pulley, *i''*, at one end. The lower carrier-shaft, *k*, is supported in three boxes, *l* *l'* *l''*, the spool and pulleys for the carrier-apron being between the boxes *l* *l'*. The inner end of the carrier-shaft *k* is provided with a miter-gear wheel, *m*, which engages the miter-gear *i'* near one end of the shaft *i*.

The carrier-frame *n* is made in two sections,

n *n'*, hinged together on their under sides, so that they may be folded, for a purpose herein-after explained. The side rails of the lower section of the carrier-frame are provided at their lower ends with bearing-arms *o*, which engage the carrier-shaft *k* outside of the boxes *l* *l'*, and are removable therefrom. The meeting ends of the side rails, *p* *p'*, are beveled on the under edges, to permit a partial folding of the sections *n* *n'* to be made, to remove the carrier-frame from the endless carrier when the stacker is to be changed from the right to the left, or vice versa. The upper section, *n'*, carries the carrier-shaft and pulleys, as in the ordinary carrier. The upper side rails of the carrier are provided with eye-bolts *q* *q'*, for the passage of the hoisting-rope *q*', which passes also through eyes *r* *r'* on the top of the thrashing-machine, and is connected to the ordinary windlass, *r''*, on the machine. A shaft and spool, *s*, work in bearings *s'* at the rear of the machine, and an endless web or apron runs over this spool and a spool on the shaft *i*, and carries the chaff to the stacker.

To change the stacker from a right-hand discharge to a left-hand discharge, the sill *b* must be removed, together with the brace-rods and stop to the sill *e'*, and the brace-rods and stop applied to that side of the machine. This change will bring the miter-gear *m* into engagement with the miter-gear *i* nearest the pulley *i''*, which is run by a belt from the main shaft of the thrashing-machine. The hinged carrier-frame is first removed from the endless slat carrier, and, when the sill has been shifted, is again applied to the lower carrier-shaft and extended within the endless slat carrier. To make this change one end of the rope must be detached from the windlass, withdrawn from the bolt-eyes, and again replaced. By this construction and arrangement the stacker can be readily changed from a right-hand to a left-hand stacker. It is cheap, simple, and durable, and is not liable to get out of order.

Having thus fully described my invention, what I claim as new, and desire to secure by Letters Patent, is—

In a straw-stacker, the combination, with 100

the thrashing-machine sill, of the removable stacker-sill, the carrier-shaft mounted on the stacker-sill, the miter-gear on its inner end, the transverse shaft at the rear of the machine, a miter-gear mounted thereon near each end, the carrier-frame, and endless slatted carrier, substantially as specified.

In testimony whereof I affix my signature in presence of two witnesses.

LEVI BOWERS.
